UNITED STATES PATENT OFFICE.

JOSEPH WOLFF, OF BROOKLYN, NEW YORK, ASSIGNOR TO SONORA PHONOGRAPH CORPORATION, A CORPORATION OF NEW YORK.

TALKING-MACHINE.

1,321,178.

Specification of Letters Patent.

Patented Nov. 11, 1919.

Application filed May 15, 1916. Serial No. 97,672.

To all whom it may concern:

Be it known that I, JOSEPH WOLFF, a subject of the King of Great Britain and Ireland, and a resident of the borough of Brooklyn, county of Kings, and State of New York, have invented a new and useful Improvement in Talking-Machines, of which the following is a specification.

My invention relates to talking machines,

10 and more particularly to the type of such machines in which a record to be reproduced is carried on a disk, and has for its object to produce a device wherein the purity and 15 sweetness of the reproduced tones will be brought out, objectionable noises such as blasting, scratching, etc., will be eliminated, and the volume of tone greatly increased.

These and further objects will more fully appear in the following specification and accompanying drawings considered together or 20 separately.

I have illustrated one embodiment of my invention in the accompanying drawings in which,—

25 Figure 1 is a top plan view of my invention, the same being inclosed in a cabinet representing an office desk;

Fig. 2 is a front elevation of the same; and

30 Fig. 3 is an enlarged sectional view of the tone-arm and a portion of the horn or diffuser.

In all of the above views, like parts are 35 designated by similar reference characters in all of the figures.

In all the drawings 1 designates a cabinet built to represent an office desk. The cabinet is provided with a hinged top 2, and with drawers or compartments 3 for storing records, needles, tools, etc.

40 Carried within the cabinet, and a short distance below the top thereof, is a partition 4, to the under side of which is secured a motor 5 of any well known type. The shaft of the motor 5 projects upward through the partition 4 and carries the usual turn-table 6 to which a record disk may be applied. The winding shaft 7 of the motor projects forward so as to be accessible for 45 winding.

The cabinet 1 below the top 2 is incased by a front panel 8, end panels 9, 10, and side panels 11, 10^a, and within the compartment so formed is disposed a horn or sound amplifier 12, of great size (not less than fifty

inches in length). The bell or discharge opening 13 of the amplifier projects through the end panel 9, and is of a size not less than twenty-four inches square. The diffuser tapers to its rear end 14, where it is upturned 60 as at 15, and extends to a point immediately below the partition 4. At this point it has an opening of not less than three inches square.

At one rear corner of the partition 4, and 65 communicating with the horn 12, is pivoted a hollow tone-arm 16, which is of extraordinary length, that is, not less than thirty inches. At its free end the tone-arm carries a sound-box or reproducer 17. The bore of 70 the tone-arm is of the same diameter as those of standard size, and increases in a series of steps from the reproducer 17 to a point near that at which it communicates with the sound-amplifier 12, where it abruptly enlarges into a bowl-shaped chamber 18, the diameter of which is approximately that of opening in the small end of the amplifier 12.

The lower end of the tone-arm is provided 75 with a circular flange which rests in a socket 19 in the partition. The socket is deeper than the thickness of the flange, so as to allow for vertical movement of the tone-arm in the socket. A plate 20 covers the socket to prevent withdrawal of the tone-arm, if 80 desired.

The lower face of the flange is provided 85 with a tapered, annular flange 21 which rests in a similarly shaped recess 22 in a block 23, which is secured to the underside 90 of the partition 4 and in which the small end of the horn is seated. The block has an opening 24 permitting communication between the tone-arm and amplifier.

The sound-box, tone-arm and horn are 95 preferably constructed of fibrous material, and I have shown them in the embodiment illustrated as composed of laminated wood, such as is shown in my co-pending application for patent filed September 1, 1915, 100 Serial No. 48,492, but I desire to have it understood that I do not desire to limit myself to such material, as the parts may be made of paper, metal or any other suitable material.

My invention consists in constructing the tone-arm and horn of great length, and in providing the abrupt enlargement of bowl shape at the outlet end of the tone-arm and in communication with the horn.

A talking machine constructed in accordance with my invention will give a great volume of sound of superior sweetness and purity, and is particularly intended for use 5 in large rooms, such as dining rooms, concert halls, hotel parlors, and the like.

While I have shown the horn or amplifier of rectangular cross-section, I desire to have it understood that the same may be made of 10 any other shape, and its bell may communicate with the outside atmosphere at the front, back or bottom of the cabinet, and that the cabinet may be constructed to represent any other article of furniture, such as 15 a table, book case, cigar counter, or cashier's desk.

A portion of the top of the cabinet is hinged to form a cover 25, which is shown opened in Fig. 1. This is to permit access 20 to the apparatus for the purpose of changing records, etc.

In accordance with the provisions of the patent statute, I have described the principle of my invention together with the 25 apparatus which I now consider to represent the best embodiment thereof, but I desire to have it understood that the apparatus shown is merely illustrative and that the invention can be carried out in other ways.

Having now described my invention, what

I claim as new and desire to secure by Letters Patent is, as follows:

1. A tone arm for a talking machine built up of sections, each section being laminated, said sections having bores of different diameters and being superposed one upon the other with an end of each section except the outermost projecting beyond that immediately beneath, whereby is produced a laminated tone arm increasing in diameter 35 step by step and with each section superposed over that immediately beneath for a distance to cause the tone arm to be made up at all points of the laminations of at least two superposed sections. 45

2. A tone arm for a talking machine built up of sections, each section being laminated, said sections having bores of different diameters and being superposed one upon the other with an end of each section except the outermost projecting beyond that immediately beneath, whereby is produced a laminated tone arm increasing in diameter 50 step by step.

This specification signed and witnessed 55 this 20th day of April, 1916.

JOSEPH WOLFF.
